COMBINED BEVERAGE SERVER AND COVER THEREFOR

Marvin Adler, Parsippany, N.J., assignor to United States Mineral Products Company, Stanhope, N.J., a corporation of New Jersey

Filed Sept. 12, 1968, Ser. No. 13,507

Term of patent 14 years

Int. Cl. D7—01

U.S. Cl. D44—21

FIG.1

FIG.6

FIG. 1 is a side elevational view of a combined beverage server and cover therefor showing my new design;

FIG. 2 is a front elevational view;

FIG. 3 is a bottom plan view;

FIG. 4 is a top plan view with the cover removed;

FIG. 5 is a reduced scale elevational view thereof, with a beverage cup shown in broken line section for purposes of environmental illustration; and

FIG. 6 is a reduced scale rear elevational view.

I claim:

The ornamental design for a combined beverage server and cover therefor, as shown and described.
